Dec. 1843

E. Elmer J. Key, of Lowell, Mass.
Assignor to

The Lowell Manufacturing Company.
Letters Patent No. 1843 Dated Nov. 10th 1863.

Design for a Carpet Pattern.

The schedule referred to in these Letters Patent and making part of the same

To all whom it may concern:

Be it known that E. Elmer J. Key,
of Lowell, in the County of Middlesex and State of Massachusetts, have originated and designed a new Pattern for Carpets or other Fabrics, of which the following is a full, clear and exact description, reference being had to the accompanying drawings, making part of this specification.

2

Dec. 1843

This pattern consists of two series of eight sided set figures enclosed by a framework of lines, dots and blocks arranged in the particular form shown in the drawings.

The colors employed for the different portions of the design, may be varied to suit the taste and wish of the manufacturer.

~ Claim. ~

What I claim as my invention and desire to secure by Letters Patent, is the Design or Pattern for Carpets or other fabrics, herein set forth.
